UNITED STATES PATENT OFFICE.

EDMUND BRUDER, OF CHICAGO, ILLINOIS.

DESIGN FOR A DISK OR ELEMENT FOR A GAME APPARATUS.

59,709.

Specification for Design.

Patented Nov. 22, 1921.

Application filed August 29, 1921. Serial No. 496,720. Term of patent 7 years.

To all whom it may concern:

Be it known that I, EDMUND BRUDER, a citizen of the United States, residing at Chicago, in the county of Cook and State of Illinois, have invented a new, original, and ornamental Design for a Disk or Element for a Game Apparatus, of which the following is a specification, reference being had to the accompanying drawing, forming a part thereof.

Figure 1 is a top plan view of the disk or element for a game apparatus.

Fig. 2 is a side elevation thereof.

Fig. 3 is a bottom plan view.

I claim—

The ornamental design for a disk or element for a game apparatus as shown.

EDMUND BRUDER.
